Primary Examiner — Bao-Yen T Nguyen*(74) Attorney, Agent, or Firm* — McAndrews, Held & Malloy, Ltd.**CLAIM**

The ornamental design for a pod for bottle spout, as shown and described.

DESCRIPTION

FIG. 1 is a front perspective view of a pod for bottle spout showing my new design;

FIG. 2 is a front view thereof, the side and rear views being identical thereto;

FIG. 3 is a top view thereof; and,

FIG. 4 is a bottom view thereof.

Views of the pod not shown form no part of the claimed design.
